UNITED STATES PATENT OFFICE.

THEODORE H. BOLTE, OF KEARNEY, NEBRASKA.

DESIGN FOR A STREET-LIGHT STANDARD.

45,851.

Specification for Design.

Patented June 2, 1914.

Application filed April 13, 1914. Serial No. 831,645. Term of patent 7 years.

To all whom it may concern:

Be it known that I, THEODORE H. BOLTE, a citizen of the United States, residing at Kearney, in the county of Buffalo and State of Nebraska, have invented a new, original, and ornamental Design for a Street-Light Standard, of which the following is a specification, reference being had to the accompanying drawing, forming part thereof.

The single view of the drawing is a per-

spective of a street light standard embodying the improved design.

I claim:

The ornamental design for a street light standard as shown.

THEODORE H. BOLTE.
